FLASHLIGHT

Filed March 16, 1928

Fig. 1.

UNITED STATES PATENT OFFICE

GEORGE H. BARBER, OF NEW ROCHELLE, NEW YORK, ASSIGNOR TO BOND ELECTRIC CORPORATION, OF NEW YORK, N. Y., A CORPORATION OF DELAWARE

FLASH LIGHT

Application filed March 16, 1928. Serial No. 262,093.

This invention relates broadly to the mounting of an incandescent lamp at the end of a flashlight casing and the like. More particularly, the invention relates to a flashlight in which the reflector and lens are removable, so that the flashlight may be stood on end with the incandescent lamp exposed, to serve as a stationary source of light and be, in effect, a candle.

10 It has been proposed to carry the incandescent lamp in a socket mounted upon a removable end for the flashlight casing, to which casing the socket is electrically and mechanically connected.

15 One electrical connection for the incandescent filament has consisted of a centrally disposed contact for engagement with the positive terminal of the battery, which contact has been resilient so as to be capable of yielding to serve as a shock absorber or thrust member to minimize the thrust of the relatively heavy battery should the flashlight fall with its top end lowermost.

20 The removable end or plate supporting the lamp socket has been secured to the flashlight casing by a connection which has involved a tubular metallic fitting or bushing secured to the end of the casing and serving as a portion of one conducting path for the electric current supplying the lamp. This bushing has had an inturned flange formed with a so-called bayonet slot by which the lamp supporting plate has been removably connected with the casing. This bayonet slot joint has 25 been formed by diametrically opposite cut away portions in the flange which receive the extremities of locking lugs, as they may be called, carried beneath the lamp socket supporting plate so that when the plate is placed in position resting on the flange with the lugs thereon passing through the cut away portions and lying in a plane below the flange, the lamp socket supporting plate may be 30 turned to bring the lugs beneath the flanges and thus securely, although removably, anchor the lamp support to the end of the battery casing.

35 The cup shaped metallic bushing in which the so-called bayonet slot is formed, has had

an outwardly extending flange on its lower edge adapted to rest on the upper end of the tube forming the battery casing. The bushing has been secured to the tube by means of a metallic hood collar formed with threads 35 to receive the reflector and other parts. This hood collar has been secured to the tube by suitable rivets, eyelets or the like, and has retained the bushing in place on the flashlight tube by engaging, by means of a flange 40 on its upper end, a fibre ring resting on the outwardly extending flange of the bushing and thereby insulating the bushing from the hood collar.

45 It will be seen that this manner of securing or mounting the bayonet slot bushing on the end of the fibre tube involves a number of operations, such as the formation of a flange on the bottom of the bayonet slot bushing, the provision of a fibre insulating ring, the provision of a hood collar, and the riveting of this hood collar to the fibre tube.

The present invention seeks to simplify the manufacture of flashlights by the omission of parts, but with the retention of all 55 the advantages and functions of the best types of structures as at present known. To this end the lamp socket and contacts are mounted upon what is, in effect, a cross bar which is removably mounted in slots or recesses formed in the walls of the battery casing, the metallic threaded hood collar serving, if desired, to close one of the slots and prevent the passage of the bar too far in that direction and the hood collar being formed 60 with an opening in register with the other slot to permit relative movement of the cross bar during its insertion or removal. One of the electric contacts serves, in known manner, as a thrust member, while the other contact 65 carried with the cross bar not only effects contact with the conductor leading, say, from the switch, but also serves as a yielding positioning element to retain the cross bar in position in the slots or recesses.

70 The invention also seeks improved contact strips for use in connection with this or any type of support for the lamp and particularly such contact strips as may function as thrust members.

In one of its aspects the invention contemplates the use of a cross-bar type lamp support with a flashlight in which the threaded hood collar is done away with and the 5 threads are formed directly on the casing. In this event the apertures receiving the ends of the cross-bar are unobstructed and the cross-bar is retained in operative position by means of one of the electrical conductors, leading, say, from the circuit controlling device on the casing.

The invention also has for its object the provision of an easily receivable or attachable lamp socket support which shall meet 10 the requirements of quantity production and assembly in manufacturing and which shall be practical and effective in use.

These and other objects of the invention and the means for their attainment will be 20 more apparent from the following detailed description, taken in connection with the accompanying drawing, illustrating embodiments thereof whereby the invention may be practiced and in which:—

25 Figure 1 is a view in vertical section showing the upper end of a flashlight with the cross bar type of incandescent lamp support forming the subject matter of this invention.

Figure 2 is a view substantially similar to 30 Figure 1 but with the reflector and its associated parts removed and the cross bar illustrated as in the act of removal.

Figure 3 is a plan view looking from above and showing one modification of the cross 35 bar lamp socket support.

Figure 4 is a plan view of the cross bar illustrated in Figure 3, but looking from below and showing the resilient contact member according to this invention.

40 Figure 5 is a section on the line 5—5 of Figure 3.

Figure 6 is a vertical sectional view of the upper end of a flashlight showing a modified form of cross bar lamp socket support.

45 Figure 7 is a plan view of the cross bar illustrated in Figure 6, looking from above.

Figure 8 is a vertical sectional view of a flashlight having the threads molded in the end thereof and including another form of 50 cross bar lamp socket support.

Figure 9 is a plan view of the cross bar shown in Figure 8, looking from above.

Figure 10 is a fragmentary view showing a modified form of contact which may be 55 availed of as a thrust member.

Figure 11 shows a cross-bar lamp socket support in a metallic casing, the cross-bar being supported by flanges defining the apertures by which the cross bar is inserted in 60 position.

Referring first to Figure 1, the metallic reflector 11, supports the lens 13 and is in turn supported upon a cylindrical hood 10 to which the lens and reflector are secured 65 by the lens ring 12 by the threaded connec-

tion 14. Tubular member or hood 10 is illustrated as removably secured, as by a threaded connection 15, to the threaded hood collar 16 which may be secured in any convenient fashion to the upper end of a tubular casing 17 70 which is preferably of insulating material and may be formed of a non-metallic substance, such as fibre.

At diametrically opposite sides of the casing 17 adjacent the top end thereof, there are formed pockets or elongated apertures 20, 21 adapted to receive, respectively, the extended end portions 22, 23 of the so-called cross-bar lamp socket support. It will be observed in Figures 3 and 4 that this cross-bar 80 member is disc-like in form at 24 to substantially close the end or opening of the flashlight casing 17, thus forming an end for the casing opening, and is formed upon diametrically opposite sides with the extended or spaced portions 22, 23 whereof the outer ends are curved as at 25, 26 upon the arc of a circle concentric with that of the disc 24 so that when this cross-bar is positioned operatively 90 in the end of the casing 17, the curvilinear ends 25, 26 will conform substantially to the outer marginal surface of the casing 17. One of these extensions or lugs 22 is shorter than the other lug 23 and is adapted to be received in the pocket or aperture 20 and to abut when 95 the disc 24 is in operative position against the threaded wall of the hood collar 16 and be positioned thereby. The other lug 23 which is the longer one, is adapted to be positioned in the opposite pocket or aperture 21 and also 100 passes through an aperture 27 formed in the threaded hood collar 12 in register with the pocket or aperture 21 in the flashlight casing 17 so that, to permit insertion or removal of the lamp support 24, it may be moved to the right as viewed in Figures 1 and 2 until the shorter lug 22 is clear of the aperture or recess 20 whereupon the longer lug 23 extends outwardly of the aperture 27 and the cross-bar 105 22-24 may be rocked in the apertures 21, 27 to permit the elevation of the opposite end of the cross bar carrying the shorter lug 22 and permit its removal in a manner readily understood upon inspection of Figure 2, the apertures 21 and 27 being of a greater dimension, longitudinally of the casing 17, to permit the biasing of the cross-bar. The threaded lower end of the hood 10 retains the cross-bar in operative position.

110 The scope of the invention which is contemplated will now be described. The pockets 20, 21 need not necessarily be in the wall of the casing 17, but any pockets having four side walls or any pockets of any form in which the lamp socket support is restrained or held against movement in all directions other than an axial direction, is within the scope of the invention. The lamp socket support in the construction described 115 as above is inserted by tilting the support so 120 125 130

that a portion of the support or a lug thereof can be inserted into one pocket far enough to enable the support to clear the wall of the casing or the inner edge of the other pocket. The other end of the support or the other lug of the support is then inserted into the other pocket. At least one of the pockets is constructed as described in order to secure the support in position in the casing and in order to insert the support therein in the tilting manner described. A lamp socket support constructed to be so inserted is readily secured in place either permanently or for subsequent removal by removing the means which retains the support in position in the pockets. Where the support is permanently secured in position, the construction takes advantage of the novel and effective manner of inserting the support, whereas where the support is also removable, the construction not only utilizes the advantages obtainable from the manner of insertion, but also takes advantage of the fact that the support is removable for inspection and repair or to enable batteries stuck within the casing to be pushed out through the top end thereof.

The cross-bar member 24 is formed with a centrally disposed aperture 30 through which the threaded end 31 of the incandescent lamp 32 may extend for electrical connection with the flashlight battery and upon its upper face the lamp support 24 carries a perforated plate or escutcheon 33 upon which the threaded lamp socket 34 is mounted which is secured 35 to the cross bar member 24 as by the eyelets 35, 36. One of these eyelets, say the eyelet 35, also carries, upon the lower face of the cross-bar 24, a contact member in the form of a flat elongated plate or strip 39 which is 40 prevented from rotation about the eyelet 35 say by the lug 40 struck inwardly into the material of which the cross-bar 24 is made and which is formed with a downwardly extending spring contact portion 41 which engages, at all times when the cross-bar is in position, the electrical conductor 42 leading from the circuit closing device 43 at the side of the flashlight casing 17.

Also, upon the lower face of the cross bar member 24, and preferably extending in a direction angularly disposed with respect to the general direction of the escutcheon 33 on the top face, is the central contact thrust member which is formed generally of two parts and comprises a strip or ribbon 44 of conducting material extending across the hole 30 in the cross bar member 24 and pressed inwardly within the hole as at 45 to serve as a bearing contact for the end 31 of the lamp 32. Beneath this strip 44 there is a generally U-shaped member 48, 50 also of metallic or conducting material secured at the arms 48, 49 together with the ends of the strip 44 immediately thereabove to the cross-bar member 24 by means of the eyelets

51 and one arm 48 of this U 48-50 is formed with an inwardly and downwardly extending resilient contact member 52 serving as a yielding or resilient shock absorbing contact for engagement with the positive terminal of the battery (not shown) as a thrust member. It will thus be seen that the circuit from the battery through the lamp includes, let us say, the positive terminal of the battery (not shown), the resilient shock absorbing contact 52 through the ribbon 44 where it contacts with the U-shaped carrier contact arm 48 to the end terminal 46 of the incandescent lamp and from the filament and threaded terminal through the socket 34 and escutcheon 33 through the eyelet 35 and strip 39 to the yielding contact conductor 42, switch 43 and then back to the negative contact of the battery (not shown), as will be understood.

The manner of insertion and removal of this cross-bar member should be readily apparent from the foregoing description. It will be appreciated that it is not permanently secured in any way to the casing 17 but is normally prevented from removal by the engagement of the threaded end 15, of the hood 10 with the one lug 23 and the engagement of the threaded hood collar 16 with the shorter lug 22 on the other side. The cross-bar is inserted by first passing the longer lug 23 while the cross-bar is tilted, as shown in Figure 2, through the opening 21 in the wall of the flashlight casing 17 and the opening 27 in the hood collar 16, a sufficient distance to permit the shorter lug 22 to pass downwardly inside of the flashlight casing and enter the recess 20. At this time the resilient contact conductor 42 is depressed and so soon as the shorter lug 22 is in register with the recess 20 and the cross-bar member is released and free to move, the tendency of the resilient contact 42 to return to normal position, causes the cross bar to shift laterally and the shorter lug 22 to enter the recess 20 and the cross-bar is retained yielding in position with the outer edge 26 of the longer lug 23 substantially flush with the outer surface of the threaded hood collar 16, so that the hood 10 may be screwed thereon and retain the cross-bar in position.

It will be noted that in order to be retained in position within the pockets, the lamp socket support must have an over-all dimension, including the portions of the support or the lugs which are inserted into the pockets, which is greater than the distance between the proximate edges of the pockets. With this over-all dimension, the lamp socket support will be supported in the pockets and must be inserted by tilting a portion or lug of the support into one pocket far enough to clear the casing with the opposite portion or lug of the support so that that portion or lug of the support is insertable in the other pocket. In the preferred construction

in which both pockets restrain the lamp socket support against transverse movement in all directions but not against axial movement, the opposite portion of the lamp socket support or lug must clear the casing until the support is opposite the other pocket or in the plane of the pockets at which time the support is moved to slide the support or lug into the other pocket.

This construction is particularly rugged, is simple and easy to manufacture and since all contacting parts include preferably a fibre or non-metallic element, there is little chance of corrosion which would prevent the ready removal of the lamp socket, which removal is sometimes necessary to permit the forcing out of the flashlight battery, in case it is distorted, by permitting the battery to be pushed from the upper end. This construction due to its simplicity is also a very much less expensive construction than that heretofore used. An added advantage of this type of cross bar construction is that the cross bar is yieldingly held in position and is capable of slight lateral movement thus absorbing to a great extent shocks and vibrations and preventing their transmission to the filament of the lamp.

A modification of the cross-bar is shown in Figures 6 and 7. This cross bar 60 is illustrated as rectangular in construction, although it will be obvious that it may take any other form between the lug-like ends 61, 62. The ends 61, 62 of this cross bar 60 are adapted to be disposed within apertures 63, 64 diametrically opposite one another in the walls of the casing 65 and the cross-bar is permanently held in place by a threaded hood collar 66 which may be secured in position say by staking portions thereof into the casing 65. The escutcheon 33 carrying the lamp socket 34 is carried on the upper side of the cross bar 60 and is riveted thereto, one of the rivets being adapted to carry a connection 67 with the circuit closing device at the side of the casing as in the previously described embodiment. Substantially transversely to the longitudinal medium line of this escutcheon 33 is a rectangular contact carrier member or frame 68 having an inwardly and downwardly directed thrust member contact strip 68' which is carried on the frame and secures and supports a contact 69 similar to that heretofore described. This device is permanently disposed within the end of the flashlight casing and is normally irremovable.

Still another modification of the cross bar is illustrated in Figures 8 and 9. This cross bar 70 is also illustrated as of generally rectangular shape and its ends 71, 72 are disposed within recesses or apertures 73, 74, diametrically disposed with respect to one another, and formed in the end of a fibre or

non-metallic tube 75 whereof the upper end has threads 76 molded therein so that no threaded hood collar is necessary. The ends 71, 72 of the cross-bar are also formed with the threads 77, to cooperate with the threads 70 formed on the fibre casing. This cross-bar 70 is yieldingly held in position by permanently securing the contact member 78 leading from the switch by means of a rivet, as before or it may be removably secured as by a bolt 79. Either securing means secures the base of the socket to lugs 80 formed on the cross bar. On the lower side of the cross bar there is a single strip of metal 81 which is not depressed into the hole 82 for the end of the lamp, but the hole is made large enough for the end of the incandescent lamp contact terminal to pass completely therethrough and contact with this strip 81, the strip 81 being secured as by the rivets 83, which also secure a downwardly extending shock absorbing contact or thrust member 84 making the contact with the positive terminal of the battery, (not shown).

A modified form of thrust member contact is illustrated in Figure 10. Across the bottom of the hole (not visible) in the cross-bar 124 is secured a strip 144 which may be wider at one end and be fastened by two eyelets 145. At the other end it may be fastened by a single eyelet 146. The eyelets 145 also secure at one end, a downwardly bent contact strip 149 similarly shaped, except for its deflected portion, and having its free end disposed short of the eyelet 146.

Instead of a fibre tube the casing may take the form of a metallic tube 90 as shown in Figure 11 formed with threads 91 for the hood 10, if desired. Diametrically opposite one another, apertures 92 may be formed in the threaded end 91 to receive any of the cross-bars heretofore described, the edges of the apertures 92 being preferably defined by inwardly directed flanges 93 as additional supports. Obviously any of the modifications hereinbefore described are applicable to a metallic casing 90.

Various modifications will occur to those skilled in the art in the composition and configuration of the component elements going to make up the invention as a whole. Certain of the elements described herein are capable of independent use or use in combination with one or more of the other elements described herein or are interchangeable and no limitation is intended by the phraseology of the foregoing description or illustrations in the accompanying drawing except as set forth in the appended claims.

What I claim is:

1. In a flashlight, the combination with a casing, of a lamp socket support, means to removably secure the support to the casing comprising recesses formed in the casing into which portions of the support extend and re-

- silient means to position the support in the casing.
2. In a flashlight, in combination, a casing formed with apertures adjacent one end, an end for the casing opening, a lamp socket carried with the end, lugs carried with the end and adapted to enter the apertures, means to close the outer side of one of said apertures, and another aperture being of a greater dimension in an axial direction.
3. In a flashlight, in combination, a casing formed with apertures adjacent one end, an end for the casing opening, a lamp socket carried with the end for the casing, lugs carried with the end and adapted to enter the apertures, means to close the outer side of one of said apertures, another aperture being of a greater dimension in an axial direction, a contact carried with the lamp support and a resilient contact carried with the casing and in engagement with said first named contact and means to close the last named aperture and retain the lamp socket supporting end in position.
4. In a flashlight, in combination, a casing formed with two diametrically opposite apertures adjacent one end, an end for the casing opening, a lamp socket carried thereby, two diametrically opposite lugs carried with said end and adapted to enter the apertures, one of said apertures being closed at its outer side and the other aperture being of a greater dimension in an axial direction.
5. In a flashlight, in combination, a casing formed with two diametrically opposite apertures adjacent its upper end, an end for the casing opening, a lamp socket supported by said end, two diametrically opposite lugs carried with said end and adapted to enter the apertures, one of said apertures being closed on its outer side, the other aperture being of a greater dimension in an axial direction, a contact carried with the lamp supporting end, a resilient contact carried with the casing and in engagement with said first named contact and means adapted to close the last named aperture and retain the lamp socket supporting end in position.
6. In a flashlight, in combination, a casing formed with diametrically opposite apertures adjacent its upper end, a hood collar secured to the end of the casing, a lamp socket supporting end for the casing opening, diametrically opposite lugs carried therewith and adapted to enter the apertures, one of said apertures being closed by the hood collar of the casing, said hood collar being formed with an aperture in register with another aperture in the casing, said last named aperture being of a greater dimension in an axial direction, a contact carried with the lamp supporting end, a resilient contact carried with the casing and in engagement with said first named contact and a hood having a portion for threaded engagement with the hood
- collar and adapted to close the last named aperture and retain the lamp socket supporting end in position.
7. In a flashlight in combination, a battery casing, pockets within the casing spaced from each other, the pockets having four side walls and the inner ends thereof being open, at least one of the pockets being large in relation to a portion of a lamp socket support received therein to receive a tilted lamp socket support, an integral lamp socket support adapted to be inserted within the casing and within the pockets, the support having a dimension including the portions insertable in the pockets greater than the distance between the proximate edges of the pockets and having a portion thereof insertable into one pocket far enough to clear the inner end of the other pocket with the opposite portion of the support, the lamp socket support being inserted by inclining the support into one pocket far enough to clear the inner edge of the other pocket and then latterly slide the support into the other pocket, a lamp socket carried by the lamp socket support, and means retaining the support against transverse movement.
8. In a flashlight in combination, a battery casing, pockets within the casing spaced from each other and spaced from the end of the casing, the pockets being unconnected with the end of the casing, the pockets having four side walls and the inner ends thereof being open, at least one of the pockets being large in relation to a portion of a lamp socket support received therein to receive a tilted lamp socket support, an integral lamp socket support adapted to be inserted within the casing and within the pockets, the support having a dimension including the portions insertable in the pockets greater than the distance between the proximate edges of the pockets and having a portion thereof insertable into one pocket far enough to clear the inner end of the other pocket with the opposite portion of the support, the lamp socket support being inserted by inclining the support into one pocket far enough to clear the inner edge of the other pocket and then latterly slide the support into the other pocket, a lamp socket carried by the lamp socket support, and means retaining the support against transverse movement.
9. In a flashlight in combination, a battery casing, pockets within the casing spaced from each other and spaced from the end of the casing, the pockets being unconnected with the end of the casing, the pockets having four side walls and the inner ends thereof being open, at least one of the pockets being large in relation to a portion of a lamp socket support received therein to receive a tilted lamp socket support, an integral lamp socket support adapted to be inserted within the casing and within the pockets, the support having a dimension including the portions insertable in the pockets greater than the distance between the proximate edges of the pockets and having a portion thereof insertable into one pocket far enough to clear the inner end of the other pocket with the opposite portion of the support, the lamp socket support being inserted by inclining the support into one pocket far enough to clear the inner edge of the other pocket and then latterly slide the support into the other pocket, a lamp socket carried by the lamp socket support, and means retaining the support against transverse movement.

- dimension including the portions insertable in the pockets greater than the distance between the proximate edges of the pockets and having a portion thereof insertable into one pocket far enough to clear the inner end of the other pocket with the opposite portion of the support, the lamp socket support being inserted by inclining the support into one pocket far enough to clear the inner edge of the other pocket and then latterly slide the support into the other pocket, a lamp socket carried by the lamp socket support, and resilient means retaining the lamp socket support in transverse position in the pockets. 10

15 10. In a flashlight, in combination, a battery containing casing formed with spaced holes proximate one end, the holes being unconnected with the end of the casing, a lamp socket support comprising a plate and a lamp socket mounted thereon, spaced portions integral with the support having a transverse dimension over the spaced portions greater than the inner dimension of the casing and adapted to be received in the respective holes, 20 the transverse spacing between the portions being less than the corresponding inner spacing of the holes so that the dimension from the inner end of at least one portion to the outer end of the other portion is less than the inner spacing of the holes whereby the said portions may freely enter into and be wholly removed from the holes upon tilting the lamp socket support in the insertion and removal thereof from the casing. 25

30 11. In a flashlight, in combination, a battery containing casing formed with spaced holes proximate one end, the holes being unconnected with the end of the casing, a lamp socket support comprising a plate and a lamp socket mounted thereon, spaced portions integral with the support having a transverse dimension over the spaced portions greater than the inner dimension of the casing and adapted to be received in the respective holes, 35 the transverse spacing between the portions being less than the corresponding inner spacing of the holes so that the dimension from the inner end of at least one portion to the outer end of the other portion is less than the inner spacing of the holes whereby the said portions may freely enter into and be wholly removed from the holes upon tilting the lamp socket support in the insertion and removal thereof from the casing. 40

45 12. In a flashlight, in combination, a battery containing casing formed with spaced holes proximate one end, the holes being unconnected with the end of the casing, a lamp socket support comprising a plate and a lamp socket mounted thereon, spaced portions integral with the support having a transverse dimension over the spaced portions greater than the inner dimension of the casing and adapted to be received in the respective holes, 50 the transverse spacing between the portions being less than the corresponding inner spacing of the holes so that the dimension from the inner end of at least one portion to the outer end of the other portion is less than the inner spacing of the holes whereby the said portions may freely enter into and be wholly removed from the holes upon tilting the lamp socket support in the insertion and removal thereof from the casing, and yielding means to cushion said support against shock in a direction substantially transverse to the axis of the casing and to retain the support in the holes. 55

60 13. In a flashlight in combination, a battery containing casing formed with spaced holes proximate one end, the holes being unconnected with the end of the casing, a lamp socket support comprising a plate and a lamp socket mounted thereon, spaced portions integral with the support having a transverse dimension over the spaced portions greater than the inner dimension of the casing and adapted to be received in the respective holes, the transverse spacing between the portions being less than the corresponding inner spacing of the holes so that the dimension from the inner end of at least one portion to the outer end of the other portion is less than the inner spacing of the holes whereby the said portions may freely enter into and be wholly removed from the holes upon tilting the lamp socket support in the insertion and removal thereof from the casing, means to close the outer side of one of said holes, and a contact carried with the lamp socket and a resilient contact carried with the casing and movable laterally thereof in engagement with the first named contact to oppose removal of a lug from a hole. 70

14. In a flashlight in combination, a battery casing formed with spaced holes proximate one end, the holes being unconnected with the end of the casing, a lamp socket support comprising a plate and a lamp socket mounted thereon, spaced portions upon the support having a transverse dimension over the spaced portions greater than the inner dimension of the casing and adapted to be received in the respective holes, the transverse dimension from the end of at least one portion to the outer end of the other portion being less than the inner spacing of the holes whereby the said portions may freely enter into and be wholly removed from the holes upon tilting the lamp socket support in the insertion and removal thereof from the casing, and removable means closing the outer side of at least one of the holes. 75

15. In a flashlight in combination, a battery casing, pockets within the casing spaced from each other, at least one of the pockets having walls restraining a support received therein against movement in all directions other than a substantially axial direction with respect to the pocket, a lamp socket support inserted within the casing and having portions thereof inserted within the pockets, the support having a dimension including the portions insertable in the pockets greater than the distance between the proximate edges of the pockets and having a portion thereof insertable into one pocket far enough to clear the opposite wall of the casing with the support and insert the other portion of the support into the other pocket, and means retaining the support in the pockets. 80

16. In a flashlight in combination, a battery casing, pockets within the casing spaced from each other, at least one of the pockets having walls restraining a support received therein against movement in all directions other than a substantially axial direction with respect to the pocket, a lamp socket support inserted within the casing and having portions thereof inserted within the pockets, 85

17. In a flashlight in combination, a battery casing, pockets within the casing spaced from each other, at least one of the pockets having walls restraining a support received therein against movement in all directions other than a substantially axial direction with respect to the pocket, a lamp socket support inserted within the casing and having portions thereof inserted within the pockets, 90

18. In a flashlight in combination, a battery casing, pockets within the casing spaced from each other, at least one of the pockets having walls restraining a support received therein against movement in all directions other than a substantially axial direction with respect to the pocket, a lamp socket support inserted within the casing and having portions thereof inserted within the pockets, 95

19. In a flashlight in combination, a battery casing, pockets within the casing spaced from each other, at least one of the pockets having walls restraining a support received therein against movement in all directions other than a substantially axial direction with respect to the pocket, a lamp socket support inserted within the casing and having portions thereof inserted within the pockets, 100

20. In a flashlight in combination, a battery casing, pockets within the casing spaced from each other, at least one of the pockets having walls restraining a support received therein against movement in all directions other than a substantially axial direction with respect to the pocket, a lamp socket support inserted within the casing and having portions thereof inserted within the pockets, 105

21. In a flashlight in combination, a battery casing, pockets within the casing spaced from each other, at least one of the pockets having walls restraining a support received therein against movement in all directions other than a substantially axial direction with respect to the pocket, a lamp socket support inserted within the casing and having portions thereof inserted within the pockets, 110

22. In a flashlight in combination, a battery casing, pockets within the casing spaced from each other, at least one of the pockets having walls restraining a support received therein against movement in all directions other than a substantially axial direction with respect to the pocket, a lamp socket support inserted within the casing and having portions thereof inserted within the pockets, 115

23. In a flashlight in combination, a battery casing, pockets within the casing spaced from each other, at least one of the pockets having walls restraining a support received therein against movement in all directions other than a substantially axial direction with respect to the pocket, a lamp socket support inserted within the casing and having portions thereof inserted within the pockets, 120

24. In a flashlight in combination, a battery casing, pockets within the casing spaced from each other, at least one of the pockets having walls restraining a support received therein against movement in all directions other than a substantially axial direction with respect to the pocket, a lamp socket support inserted within the casing and having portions thereof inserted within the pockets, 125

25. In a flashlight in combination, a battery casing, pockets within the casing spaced from each other, at least one of the pockets having walls restraining a support received therein against movement in all directions other than a substantially axial direction with respect to the pocket, a lamp socket support inserted within the casing and having portions thereof inserted within the pockets, 130

the support having a dimension including the portions insertable in the pockets greater than the distance between the proximate edges of the pockets and having a portion thereof insertable into one pocket far enough to clear the opposite wall of the casing with the support and insert the other portion of the support into the other pocket, and means retaining the support against transverse movement and removable from retaining position.

16. In a flashlight in combination, a battery casing, pockets within the casing spaced from each other, at least one of the pockets having walls restraining a support received therein against movement in all directions other than a substantially axial direction relatively to the pocket, a lamp socket support adapted to be inserted within the casing, spaced lugs upon the lamp socket support insertable within the pockets, the support having a dimension including the lugs greater than the distance between the proximate edges of the pockets, one of the lugs being insertable into one pocket far enough to insert the other lug into the other pocket, and means retaining the support in the pockets.

30 In testimony whereof I affix my signature.
GEORGE H. BARBER.
